CLAIM

The ornamental design for a night table, as shown and described.

DESCRIPTION

FIG. 1 is a front elevational view of a night table showing my new design;

FIG. 2 is a right side elevational view, the left side being a mirror image thereof;

FIG. 3 is a perspective view thereof with the hinged top shown in a closed position; and

FIG. 4 is a perspective view corresponding to FIG. 3 but showing the hinged top in an open position.

The undisclosed rear of the night table is similar in appearance to the FIG. 1 showing.

FIG. 1

FIG. 2

FIG. 3

FIG. 4
